US0D1096457S

(12) **United States Design Patent** (10) **Patent No.:** **US D1,096,457 S**
Chen (45) **Date of Patent:** **** Oct. 7, 2025**

(54) **TEMPERATURE AND HUMIDITY DATA LOGGER**

(71) Applicant: **Jiangsu Jingchuang Electronics Co., Ltd.**, Jiangsu (CN)

(72) Inventor: **Changdong Chen**, Jiangsu (CN)

(***) Term: **15 Years**

(21) Appl. No.: **35/523,191**

(22) Filed: **Aug. 10, 2024**

(80) **Hague Agreement Data**

Int. Filing Date: **Aug. 10, 2024**

Int. Reg. No.: **DM/242157**

Int. Reg. Date: **Aug. 10, 2024**

Int. Reg. Pub. Date: **Dec. 6, 2024**

(57) **CLAIM**

The ornamental design for a temperature and humidity data logger as shown and described.

DESCRIPTION

The file of this patent contains at least one drawing/photograph executed in color. Copies of this patent with color drawing(s)/photograph(s) will be provided by the Office upon request and payment of the necessary fee.

1. Temperature and humidity data logger

1.1 : Front

1.2 : Back

1.3 : Left

1.4 : Right

1.5 : Top

1.6 : Bottom

1.7 : Perspective

FIG. 1.1 is a front view of a temperature and humidity data logger embodying our new design; FIG. 1.2 is a back view thereof; FIG. 1.3 is a left view thereof; FIG. 1.4 is a right view thereof; FIG. 1.5 is a top view thereof; FIG. 1.6 is a bottom view thereof; FIG. 1.7 is a perspective view thereof.

1 Claim, 7 Drawing Sheets
(7 of 7 Drawing Sheet(s) Filed in Color)
